HERRMANN MENGEL, OF PHILADELPHIA, PENNSYLVANIA.

Letters Patent No. 61,349, dated January 22, 1867.

IMPROVEMENT IN INSTRUMENTS FOR GUIDING TAILORS IN CUTTING OUT COATS AND VESTS.

The Schedule referred to in these Letters Patent and making part of the same.

TO ALL WHOM IT MAY CONCERN:

Be it known that I, HERRMANN MENGEL, of Philadelphia, Pennsylvania, have invented an Instrument for Guiding Cutters-Out of Coats and Vests; and I do hereby declare the following to be a full, clear, and exact description of the same, reference being had to the accompanying drawing, and to the letters of reference marked thereon.

My invention consists of the combination of adjustable graduated strips, fully described hereafter, whereby the shape of pieces of fabric for making coats and vests can be readily and accurately determined.

In order to enable others to make and use my invention, I will now proceed to describe its construction and operation. On reference to the accompanying drawing, which forms a part of this specification—

Figure 1 represents my improved instrument for guiding cutters-out of coats and vests, the parts in this view being adapted to the marking out of the front pieces of vests.

Figure 2, a view of the instrument, modified in form, and arranged to facilitate the cutting out of the back pieces of a vest; and

Figure 3, a diagram, showing the points on the body where measurements must be made in order that the instrument may be properly adjusted.

A and B (fig. 1) are thin plates of metal or other suitable material, which are so secured together as to be adjustable longitudinally in respect to each other; and to the plate B are secured two adjustable strips, C D. An adjustable strip, E, of the form shown in the drawing, is secured by a pin, e, to one end of the plate A, on which are engraved or marked three scales, 1, 2, and 13. On the plate B is a scale, 3, and on the strips C D and E are scales 4, 5, 6, 7, 8, 9, 10, 11, and 12, all the said scales being arranged and graduated as shown in the drawing. In the modification of the instrument shown in fig. 2 the plates A' and B' are secured together so as to be adjustable in respect to each other, in the same manner as the plates A and B, and from one end of the plate B' project two arms, G G'. To the plate B' is secured an adjustable strip, c', and to one end of the plate A' is secured an adjustable strip, E', of the form shown in the drawing. On the plates A' and B' are scales, 14, 15, 16, 17, 18, and 27, and on the strips C' and E' are scales 19, 20, 21, 22, 23, 24, 25, and 26, which are arranged and graduated as shown in the drawing.

Before proceeding to cut a garment from a piece of cloth, the following measurements must be taken of the person for whom the garment is intended:

1. From the point *a* to the point *a'* (fig. 3) over the shoulder. In a well-formed person this distance is generally about fifteen inches.
2. From *a* to *b*, at a point back of the neck, as high as the collar is to extend, about twelve inches.
3. From *a* to *d*, (the hip,) about nine inches.
4. From *a* to *c*, at the middle of the back, about twelve inches.
5. Round the chest, at the height of *a*, about thirty-six inches.
6. Round the waist, just above *d*, about thirty-two inches.
7. From *b* to waist in front, as far down as the point of the vest is to extend.
8. From *a'* to *b*, about ten inches.

The instrument is now placed on the cloth, and arranged as shown in fig. 1, the parts being adjusted according to the measurements as follows: The graduated edge of the strip D is supposed to represent the position of the line *a a' c*, and as the first measure, from *a* to *a'*, over the shoulder, is fifteen inches, the plate B is adjusted so that the edge of the strip shall be even with the line 15 on the scale 1. The distance from *a* to *c* being twelve inches, the strip D is adjusted so that the line 12 of the scale 9 shall be even with the edge of the plate A; a mark is then made on the cloth at *g*, at the end of the strip D. As the measure from *a* to *b* is twelve inches, the strip E is adjusted until its lower edge *z* is even with the line 12 on the scale 13; and as the distance from *a* to *d* is nine inches, the strip C (the edge of which is supposed to represent the position of the line round the waist at *d*) is adjusted until its upper edge is even with the line 9 of the scale 3. A line, *m*, is now drawn on the cloth, with the edge of the strip as a guide, and the strip is inclined in proportion to the extent to which the point of the vest is to descend below the waist line. As the distance round the chest is thirty-six inches, the cloth is marked at the points *y¹ y² y³ y⁴ y⁵ y⁶*, opposite the lines 36 in the scales 2, 12, 10,

11, and 8; and as the distance round the waist is thirty-two inches, marks are made on the cloth at the points $y^7 y^8 y^9 y^0$, opposite the line 32 in the scales 5, 4, 6, and 7. The instrument is now removed from the cloth, and straight lines are drawn between the points $y^3 y^4$ and y^5 and y^6 . Curved lines are then drawn between the points y^1 and $y^4 y^5$, a line slightly curved is drawn from y to y^9 through y^0 , and another from y^8 to y^9 through y^6 and y^7 ; a line is then drawn from y^3 to y^1 through y^2 . The cloth is then cut on or near these lines, and the piece thus detached will be of a proper shape to form one-half the front of the vest; the corresponding half may then be marked and cut from that first made. The instrument of the modified form shown in fig. 2 is then laid on the cloth, and is adjusted as follows: The edges of the arms $G^1 G^2$ are supposed to represent the position of the breast line $a a'$, and the edge of the strip C' the position of the waist line d ; the strip C' is therefore brought to a position even with the line 9 in the scale 16, inasmuch as the lines $a a'$ and d , according to the third measurement, are nine inches apart. As the distance from a to a' over the shoulder is fifteen inches, the plate B is adjusted until the edge of the arm G^2 is even with the line 15 in the scale 27; and as the distance from a' to b is ten inches, the strip E' is adjusted until its edge, x' , is even with the line 10 in the scale 15. As the breast measure is thirty-six, marks are made on the cloth at the points $z z^1 z^2 z^3 z^4$, opposite the lines 36 in the scales 22, 21, 20, 19, and lines are drawn on the cloth between the points $z z^1 z^2 z^3 z^4$, the edges of the strip E' serving as guides. If, however, the breast measure was less than thirty-six inches, (thirty-four, for instance,) the marks on the cloth should be made to correspond to the lines 34 in said scales. As the distance from a to c is twelve inches, the cloth is marked at z^1 and z^2 , opposite the lines 12 on the scales 17 and 18; and as the waist measure is thirty-two inches, the cloth is marked at the points $y^7 y^8 y^9 y^0$, opposite the lines 32 in the scales 23, 24, 25, 26. The instrument is then removed from the cloth, and a curved line is drawn from the point z^2 through the point z^3 to the point z^4 ; a line slightly curved is drawn from z^2 through z^3 to z^4 , a slightly curved line is drawn from z^3 to z^4 , and another from z^4 to z through the points $z^0 z^1$. The cloth is now cut at or near the lines marked on the same, the piece thus detached being of the proper size and shape to form one-half the back of the vest. The corresponding half is then cut from the cloth, using the first as a pattern.

When the measurements of the person for whom the garment is intended differ from those named, the parts of the instrument are adjusted accordingly, and the marks and lines on the cloth are drawn between other points on the scales. A similar instrument, having scales with longer degrees, may be used for facilitating the cutting of coats and outer garments.

Without confining myself to the precise construction and arrangement of parts herein described, or to any special arrangements or graduation of the scales, I claim as my invention, and desire to secure by Letters Patent—

A plate A and adjustable strip E , in combination with an adjustable plate B , adjustable strip C , and strip D , or its equivalent, the whole being constructed, graduated, and arranged substantially as and for the purpose described.

In testimony whereof I have signed my name to this specification in the presence of two subscribing witnesses.

HERRMANN MENGELE.
